UNITED STATES PATENT OFFICE

STEN WADSTEN, OF BLOOMFIELD, NEW JERSEY, ASSIGNOR TO WESTINGHOUSE LAMP COMPANY, A CORPORATION OF PENNSYLVANIA

MACHINE FOR MAKING SPACED COILED FILAMENTS

Application filed July 26, 1928. Serial No. 295,536.

The present invention relates to an improvement in coil winding machines for making spaced coils and relates more particularly to a machine employing a wire coiling element of the character set forth in my copending application Serial No. 246,294, filed January 12, 1928.

It is desirable in the manufacture of a coiled body, especially in the case of producing a helix for use as a light source for incandescent electric lamps, to produce the coiled body in the absence of a mandrel. A coiled body such as a light source or lamp filament when produced without the aid of a mandrel may be manufactured at a lower cost and higher speed inasmuch as the operation of removing the mandrel is eliminated. A machine for producing a coiled filament body, as for instance a lamp filament, is shown and described in Patent 1,670,499. The above mentioned copending application, however, shows an improved form of coil winding die which may be used in connection with the machine disclosed in the said patent.

The coil winding die, as set forth in the said copending application, is produced by providing a coiled wire helically wound upon a mandrel and with the turns of the coil in contacting relation so as to make what is termed a closed coil. This coil is used as a primary embossing matrix and is suitably supported so that a pair of die blanks, in the form of discs of relatively soft metal, may be disposed with their edges or peripheries in contact with opposite sides of the coil. The blanks may then be rotated in the presence of sufficient force to compress them upon the embossing matrix during a rolling movement of the blanks over the matrix, which movement may continue until an initial depression is obtained in the blanks.

Another or second embossing matrix may then be provided by winding a wire upon a mandrel with the spaced relation of the turns of the coil of a predetermined degree or pitch in accordance with the desired pitch to be obtained in the die produced and consequently in the coil produced by means of the die. Blanks with the initial depression therein may then be rolled over the second embossing

matrix in the presence of sufficient force to compress the blanks with an impression of the properly spaced coil. The blanks may then be hardened and employed as coil winding elements or dies in a mandrelless coil winding machine.

In the manufacture of certain types of incandescent electric lamps, the light source or filament therefor is formed from a highly refractory wire such as tungsten, coiled to helical form. Certain types of filaments are wound in continuous helixes and severed to given lengths, each length being of such dimensions as to have the required resistance for a given type lamp. Filaments of this character are usually secured to the leading-in conductors of the lamp by clamping or welding directly to the coiled end of the sections. When securing a completely coiled section to a leading-in wire, certain disadvantages arise in that the clamping or welding operation may include more or less of the coiled sections thus changing the effective filament length and consequently changing the resistance of the element to the end that the desired rating of the filament is altered.

It is desirable, therefore, in certain cases, to produce a coiled section having straight portions as terminals so that the welding or clamping operation for securing the ends of the coiled section to the lead-in wire is facilitated. When straight ends are provided as terminals for a filament, the welding or clamping operation, to secure the filament to leading-in conductors, may be accomplished in a more uniform manner, thus making the mounting operation more accurate.

Heretofore, filament wire has been wound to helical form so as to produce a series of sections of closely wound turns of wire separated by one or more turns of greater pitch than the turns composing the closely wound sections, thus providing relatively closely wound sections of wire terminating in uncoiled or comparatively straight portions. The above operation, however, has previously been performed on what is known as a mandrel wound coil winding machine and the spacing of the coils was accomplished by

changing the relative movement of the mandrel and the degree of rate of winding.

It is an object of the present invention to provide means for supporting and manipulating the above described coil winding die so as to produce a plurality of coiled sections of a given pitch separated by sections of a different or greater pitch.

Another object of the invention is to provide a machine for automatically winding coiled sections separated by uncoiled portions of wire.

Other objects and advantages of the invention will be more fully understood from the following description, together with the accompanying drawing, in which:

Figure 1 is a plan view of a portion of a coil winding machine showing the present coil winding die in operative relation thereto;

Figure 2 is a side view of the mechanism shown in Figure 1;

Figure 3 shows a modified form of means for holding the die to produce spaced coils in accordance with the present invention;

Figure 4 is a side view of the die and support shown in Figure 3;

Figure 5 is a top view of the die and support shown in Figure 3;

Figure 6 is an enlarged view of a coil winding die in position to receive the wire from the driving roller;

Figure 7 is a fragmentary view of the die shown in Figure 6 and illustrates different relative positions between the die and the driving rollers; and

Figure 8 is a fragmentary side view of the die in position adjacent to the driving rollers.

Although the present form of coil winding die may be associated with various types of mechanism for driving a wire, it is shown and described in connection with a coil winding machine of the character disclosed in the above mentioned patent, in which a pair of driving rollers 10 and 11 are provided to drive a wire 12 which may be received from a spool or any other suitable source not shown. The rollers 10 and 11 are rotated at high speed by suitable means, not shown, in the present drawing. The roller 10 is mounted in a plate 13 hinged at 14 in bearings 15 and 16 and the roller 11 is journaled in the frame of the machine. The rollers 10 and 11 are provided with circumferential grooves 10' and 11', each having a depth slightly less than the diameter of the wire so as to frictionally engage the same when the plate 13 is in position to dispose the roller 10 adjacent to the roller 11.

A rotation of the rollers 10 and 11 causes a movement of the wire 12 toward a die 17, more clearly shown in Figures 6 to 8, so that the wire engages with a groove 18 and issues from the die in the form of a coil 19. When the driving rollers are continuously operated

to drive the wire into the die, a continuous helix is produced.

For the purpose of intermittently terminating the coiling operation, means are provided for changing the relative position of the die and the rollers at intervals. This means may comprise a plunger 20 slidable in a bearing 21. The die may be mounted on a pin 22 at an upper end 23 of the plunger and may be provided with a ratchet wheel 24 engageable with dogs 25 and 26 pivoted on the bearing 21. The ratchet mechanism is provided so that the die will be normally held in a given position and by means of an adjustment of the dogs the die may be rotated to position a new groove for a coil winding operation. The bearing 21 is mounted on a bracket 27 pivotally connected at 28 to a shaft 29 loosely fitted in a bearing 30. The bracket 27 is provided with an extension 31 having an arm 32 provided with a split collar 33 surrounding the plunger 20 to provide a guide bearing.

The lower end 34 of the plunger 20 is provided with a swivel connection 35 having an arm 36 pivotally connected to one end of a lever 37 pivoted at 37', the opposite end of the lever being pivotally connected to an end 38 of a push rod 39. This push rod may be supported in bearings 40 and 41 and is provided with a beveled lifter plate 42, an end of which is disposed beneath a projection 43 integral with the plate 13 so that a movement of the lifter plate 42 results in slightly elevating the plate 13, thus lifting the roller 10 from engagement with the wire 12 and terminating the movement of the wire toward the guide.

The lifter plate 42 is provided with a slot 44 through which a pin 45 extends, the plate 42 being slidable along the push rod and adjustable by means of a set screw 46. Thus the lifter plate may be adjusted so as to lift the roller 10 exactly the proper amount to release the wire without permitting the wire to escape from between the grooves 10' and 11'.

The mechanism for causing a movement of the lifter plate may comprise the cam 47 mounted on a shaft 48 and rotated in timed relation to the other mechanism by suitable connection, not shown. The cam 47 engages an abutment 49 secured to the push rod 39, a spring 50 serving to normally maintain the abutment in contact with the cam. Thus a rotation of the shaft 48 will cause the push rod to move in the direction of the arrow X, thereby moving the plunger 20 downwardly carrying the die away from the rollers.

After a section of wire has been wound containing the proper number of turns, the cam operates causing the push rod to function to remove the die a predetermined distance from the driving rollers. When the die has reached its lower position, the lifter plate

operates to terminate the movement of the wire and a continued rotation of the cam will permit the spring to bring the die back to its coil winding position and the lifter plate will cause the roller 10 to engage with the wire and the coil winding operation will be continued. It has been found that after a series of coils are wound and the coil winding operation is interrupted intermittently at given intervals by reason of the formation of the cam a plurality of coiled sections are produced, separated by sections of substantially straight wire or wire having a coil of an extremely large pitch.

It will be noted that when the lever 37 is oscillated to cause a reciprocal movement of the push rod, a slight rocking action is imparted to the die 17 since the supporting structure for the die is movable on shaft 29 in bearing 30. This rocking or sidewise movement of the die tends to dislodge a coiled section or slightly bend the wire adjacent to the said section so that after the die has been lowered and then returned to its operating position the starting of a new section will be facilitated. After a number of coils have been formed or after each coil is made, mechanism may be provided for cutting the wire intermediate the coiled sections.

The above described mechanism illustrated one means for interrupting the coil winding movement by a bodily movement of the die with respect to the driving rollers. In Figures 3 to 5, however, mechanism is provided wherein a die 17 is mounted on a spindle 51 carried at one end of a bracket plate 52. Secured to the die is a rigid wheel 53 and adjacent to the rigid wheel and pivotally connected to the spindle 51 is a rocker arm 54. A dog 55 is pivotally mounted on the rocker arm at 56 and held in contact with the teeth of the ratchet wheel 53 by a spring 57. An oscillation of the rocker arm 54 operates to cause an intermediate rotary movement of the die. Mechanism for rocking the arm 54 may comprise a cam 58 mounted on a shaft 59 driven through any suitable source of power, not shown. The cam 59 is engageable with a lug 60 on the arm 54 and a spring 61 normally maintains the lug in contact with the cam. The arm 54 is provided with an extension 62 having a guide slot 63 to receive a pin 64 extending from the bracket 52.

In operation the driving rollers 10 and 11 propel the wire 12 into a groove in the die 17 and after a predetermined number of coils have been wound the cam member 58 permits the spring 61 to act causing the lifter mechanism to move the die in the direction of the arrow Y, thus causing the coiled sections to move away from the path of movement of the straight wire which continues to move into the die to produce another coiled section. It has been found that coiled sections separated by uncoiled sections or sub-

stantially straight portions, can be produced by a sudden displacement of the coil winding die and if this displacement occurs as in accordance with the present invention at predetermined intervals, a series of coiled sections will be produced separated by substantially straight portions. It is to be understood that the number of coils in a section may be varied and that the cam 58 may be changed or that the movement or stroke of the rocker arm 54 may be altered in accordance with the number of coils to be produced in a section and that the straight portion between the coils may be varied by varying the rotary movement of the die.

The above invention operates to utilize a coil winding die and provide means whereby the die may be intermittently adjusted with respect to the driven wire for the production of coiled sections separated by substantially straight or uncoiled sections.

Although a preferred embodiment of the invention is shown and described herein, it is to be understood that modifications may be made therein without departing from the spirit and scope of the appended claims.

What is claimed is:

1. A coil winding machine comprising means for moving a wire, mandrelless coil winding means and means for intermittently terminating the coiling operation to produce uncoiled portions of wire connecting coiled portions.

2. A coil winding machine comprising means for moving a wire, a coil winding die and means for intermittently causing a change in the relative positions of said means and die to produce uncoiled portions of wire connecting coiled portions.

3. A machine of the class described comprising means for moving a wire through a given path, a wire coiling die in the path of movement of said wire to produce a coiled section and means for causing a movement of said die to interrupt the coiling operation.

4. A machine of the class described comprising means for moving a wire through a given path, a wire coiling die disposed to receive and coil said wire and means for changing the relative positions of said first mentioned means and said die to produce coiled sections separated by uncoiled portions of wire.

5. A machine of the class described comprising means for driving a wire through a given path, wire coiling means and means for causing a movement of said wire coiling means away from said wire driving means, means for terminating the movement of said wire, and means for moving said wire coiling means toward said wire driving means.

In testimony whereof, I have hereunto subscribed my name this 25th day of July, 1928.
